UNITED STATES PATENT OFFICE.

HENRY W. PARTON, OF YONKERS, NEW YORK, ASSIGNOR TO ALEXANDER SMITH & SONS CARPET COMPANY, OF SAME PLACE.

DESIGN FOR A CARPET.

SPECIFICATION forming part of Design No. 14,311, dated September 18, 1883.

Application filed May 4, 1883. Term of patent 3½ years.

To all whom it may concern:

Be it known that I, HENRY W. PARTON, of Yonkers, Westchester county, State of New York, have invented a new and original Design for Carpets, of which the following is a specification.

The accompanying photograph illustrates my new design for carpet.

This invention relates to a new design for carpets, oil-cloths, and analogous fabrics; and it consists of the new ornamentation of parts hereinafter more fully pointed out.

On the background of the carpet are the representations of coral-like figures *a*, *b*, *c*, *d*, and *e*. Some of these carry floral ornaments.

Thus near the coral-like figure *e* is the floral group *f*, and near the coral-like figure *c* is the floral group *g*, while the group *h* is near the figure *d*, joining it, practically, to a leaf-like figure, *i*. *j* is a floral group placed above the figure *d*, as shown, and joining it to a leaf-like figure, *l*, which is the duplicate of figure *c*.

I claim—

The design for carpets, consisting of the figures *a b c d e f g h i j l*, substantially as shown. 25
